Specification for Design.

Patented Oct. 25, 1921.

Application filed March 28, 1921. Serial No. 456,496. Term of patent 7 years.

To all whom it may concern:

Be it known that I, CURTIS A. SMITH, a citizen of the United States, residing at New Rochelle, in the county of Westchester and State of New York, have invented a new, original, and ornamental Design for a Ring for Lighting-Fixtures, of which the following is a specification, reference being had to the accompanying drawing, forming part thereof.

The figure is a side view of a ring for lighting fixtures, embodying my new design.

I claim:

The ornamental design for a ring for lighting fixtures, as shown.

CURTIS A. SMITH.
